Attorney

UNITED STATES PATENT OFFICE.

EZRA FISHBURN, OF OVERBROOK, KANSAS.

VEHICLE-WHEEL.

No. 893,715.

Specification of Letters Patent.

Patented July 21, 1908.

Application filed September 10, 1907. Serial No. 392,094.

To all whom it may concern:

Be it known that I, EZRA FISHBURN, citizen of the United States, residing at Overbrook, in the county of Osage and State of Kansas, have invented certain new and useful Improvements in Vehicle-Wheels, of which the following is a specification.

My invention relates to improvements in cushion tired vehicle wheels adapted to be used on automobiles, bicycles, and similar vehicles, and the object of the invention is to simplify, improve and reduce the cost of construction to a minimum and provide a wheel which will be strong and durable in its construction.

With these and other objects in view, the invention consists in the combination and aggroupment of parts, as will be hereinafter more in detail described and specifically claimed.

In the accompanying drawings to which reference is had and which fully illustrate my invention, Figure 1 is a cross sectional view of a wheel showing the location and aggroupment of the several parts. Fig. 2 is a sectional view of a portion of the wheel broken away, showing the spring sections of the several parts, Fig. 3, is a detached view of one of the upper movable plates and Fig. 4, is a modification of the plates shown in Fig. 3.

Similar letters of reference indicate corresponding parts throughout the several views.

Referring to the drawings, A designates a peripheral covering of rubber or other substantial material and which is secured by means of lacing or in any suitable manner, as at b.

B designates a cushion tire interposed between the covering A and a number of T-shaped upper movable plates C, arranged serially in sections within the covering and around the wheel. Through the tire is passed a series of cable wires C clearly shown in Fig. 1 of the drawings. These plates C are provided upon their inner surfaces with thimbles c which engage the upper ends of coil springs D. E designates lower duplicate right angular or L-shaped stationary plates, upon the inner and horizontal surfaces of which are secured thimbles of sufficient depth to engage and securely hold the lower ends of the coil springs D in place, hereinbefore mentioned, these thimbles effectually preventing the displacement of said springs during the reciprocating action of the upper

T-shaped plate C, the arrangement of the lower plates E being such as to allow sufficient space between the vertical portions of said plate for the tongue or web c of the upper T-shaped plate to be projected and play 60 therein as the pressure upon the spring located between the rims and plates require, when the wheel is in motion.

F designates a felly, around which is secured a metallic band G, said band being interposed between the lower L-shaped plates E and the felly, and to which said plate E, is secured.

H designates an inner rim secured to the felly in the ordinary manner.

In Fig. 4 I have shown a modification of the operative plates illustrated in Fig. 3, wherein the numeral 1 designates an upper reciprocating, horizontal plate having its ends 2, 3 bent downwardly at right angles toward the body portion thereof, and provided centrally upon its inner surface with a tongue or web 4. 5 and 6 designate lower stationary plates, having their ends 7, 8 turned upwardly at right angles to the body portions 5, 6. By such construction and arrangement of these plates, a space or groove is formed between 5 and 6, within which is projected a tongue or web 4 of the movable reciprocating plate 1. The object of the downwardly 85 and upwardly bent ends of these plates is to give greater strength to and to resist side pressure of these parts during their operation.

Having thus described my invention, what I claim as new and desire to secure by Letters Patent, is:

1. In a vehicle wheel, the combination with the peripheral covering secured together with lacing to the felly of the wheel, a cushion tire, cable wires passed through said tire, a felly, a metal band passed around said felly of angular lower stationary and upper movable T-shaped plates, thimbles secured to the inner surfaces of the upper T-shaped 95 movable plates and the angular lower stationary plates and springs having their ends located in the thimbles.

2. In a vehicle wheel, the combination with the peripheral covering secured together with lacing to the felly of the wheel, a cushion tire, cable wires passed through said tire, a felly, a metal band passed around said felly, angular lower stationary and movable upper T-shaped plates the latter being in movable 105 110

connection with the band, thimbles secured to the inner surfaces of the upper T-shaped movable plate and the angular lower stationary plates, coiled springs located between 5 the upper and lower plates, and held in said thimbles secured to the inner surfaces of said plates, and an inner rim secured to the felly.

In testimony whereof I affix my signature, in presence of two witnesses.

EZRA FISHBURN.
